UNITED STATES PATENT OFFICE.

CHARLES G. FRAVEL, OF PLAIN TOWNSHIP, FRANKLIN COUNTY, OHIO, ASSIGNOR OF
ONE-HALF TO ALGERNON E. BENNETT, OF WESTERVILLE, OHIO.

SHOCK-TIER.

1,073,035.

Specification of Letters Patent. Patented Sept. 9, 1913.

Application filed July 8, 1909. Serial No. 506,477.

To all whom it may concern:

Be it known that I, CHARLES G. FRAVEL, a citizen of the United States, residing at Plain township, in the county of Franklin and State of Ohio, have invented a certain new and useful Improvement in Shock-Tiers, of which the following is a specification.

The primary object of this invention is 10 to provide a simple, cheap and economical fodder tier but the invention can be used for tying things or material other than fodder.

The invention is embodied in the construction herein shown and described and pointed out in the appended claim.

In the accompanying drawing Figure 1 is side elevation of the device showing a cord secured in the tier member proper. 20 Fig. 2 is a plain view of the tier member with a fraction of the cord attached thereto. Fig. 3 is an elevation of the coil end of the tier member proper.

The tier member proper comprises a coil 25 portion 4 and a shank portion 5. These portions 4 and 5 are bent out of a single piece of suitable stiff wire. The coil portion consists of about one and a half cycles of wire with an end left standing off at a 30 tangent as seen at 4^a to facilitate the insertion of the cord in tying a bundle. The shank portion 5 is bent to stand at right angles to the coil portion and into the form of an eye, as seen at 5^a to afford a 35 convenient device for attaching an end of the cord as seen in Figs. 1 and 2.

6 designates the cord.

In tying a bundle the free end of the cord is passed around the bundle and drawn tight. After this it is wrapped one or more 40 times around the shank 5 and then passed in between portions of the coil and drawn tight. The coils pinch the cord and effectively prevent the cord from slipping loose, and it can only be detached by proper 45 manipulation. The coil members can be furnished to husbandmen in quantities and ordinary twine such as is used as binders added by them in spare moments.

I do not confine myself to the exact form 50 of the device shown but modifications may be made therein within the scope of the appended claim.

What I claim is:

A device for tying shocks or bundles, said 55 device formed of a single piece of wire and comprising, in combination, a coil portion 4 the strand of which terminates at one side of the coil in a tangential portion 4^a to permit insertion of a cord between the members of the coil, and at the other in a shank 60 5 extending from the coil in a right line and at right angles to the plane of the coil, said shank provided at its free extremity with an eye, 5^a, to receive a cord, and said 65 shank and coil at their junction forming a corner around which the free end of the cord may be passed for insertion between the members of the coil, substantially as described.

CHARLES G. FRAVEL.
